UNITED STATES PATENT OFFICE.

WALTER I. KIRK, OF CHICAGO, ILLINOIS.

HARP.

Application filed August 19, 1921. Serial No. 493,626.

To all whom it may concern:

Be it known that I, WALTER I. KIRK, a citizen of the United States, residing at Chicago, in the county of Cook and State of Illinois, have invented a certain new and useful Improvement in Harps, of which the following is a full, clear, concise, and exact description, reference being had to the accompanying drawings, forming a part of this specification.

My invention relates to harps and particularly to means for controlling the strings thereof.

One of the objects of the invention is to provide a simple, practical and effective construction of harp.

Another object of the invention is to provide means for controlling one or more strings so as to damp the same.

Another object of the invention is to provide such damping means which will damp practically all the strings of the harp.

Another object of the invention is to provide practical and effective means for controlling such damping arrangement.

Another object of the invention is to permit the operation of the damping means either by foot power or manually.

In the accompanying drawings Fig. 1 is a side elevation of a harp embodying my present invention;

Fig. 2 is a cross section taken on lines 2—2 in Fig. 1;

Fig. 3 is a vertical section of the lower portion of the harp;

Fig. 4 is a longitudinal section on an enlarged scale of an upper portion of the harp;

Fig. 5 is a cross section taken on line 5—5 in Fig. 4;

Figs. 6 and 7 are cross sections taken on lines 6—6 and 7—7 in Fig. 1;

Figs. 8 and 9 are views of details of construction;

Fig. 10 is a view of a pedal mechanism for operating the damper;

Fig. 11 is a view of an upper part of the harp;

Figs. 12 and 13 are views of details of construction;

Fig. 14 is a cross section taken on line 14—14 in Fig. 13;

Fig. 15 is a plan view of the mechanism shown in Fig. 14; and

Fig. 16 is a view of a detail of construction.

Fig. 17 is a view of a detail of construction.

Referring to the drawings, and especially Fig. 1, I show a harp A having a base 1, a body 2, column 3, neck 4, and strings 5—5. The construction of these parts may be varied.

In accordance with my invention I provide a damper arrangement by which one or more, preferably almost all of the strings 5, may be damped. The arrangement shown comprises a damping device or damper 6 preferably in the form of a rod or bar having a curvature substantially corresponding with the under side of the neck 4 and mounted near such under side of the neck so that it may be moved back and forth to and away from the strings 5, so that when the damper 6 is against the strings 5 the same will be damped, and when moved away from the strings, the latter will be free to vibrate in the usual or normal manner.

The mounting for permitting the support of the damper 6 and also the movement of the same toward and away from the strings 5, preferably involves a plurality of substantially aligned brackets 7—7, (Figs. 1, 4, 14 and 15). Each of these brackets 7 is provided with upwardly extending arms 8 and 9, which are secured as by screws 10—10 to frame pieces 11 and 12, respectively, forming part of the neck 4. In each one of these brackets 7 is mounted a bolt 13, one end of which 14 is provided with worm threads, and the other end of which is mounted in a bearing 15 in the bracket arm 9. Said other or small end of the bolt 13 projects from the outer side of the arm 9 and is connected with the damper 6 by means of a screw 16 fitted into said end of the bolt 13. The thread for the screw 16 is left handed and a collar 17 is fitted over the end of the bolt 13 and a washer 18 arranged next to the outer surface of the arm 9. A coiled spring 19 encloses the intermediate portion of the bolt 13. A sleeve 20 is fitted over the threaded end 14 of the bolt 13, the interior of the sleeve 20 being correspondingly threaded. A projection or arm 21 or 21^a is arranged at the inner end of the sleeve 20, being preferably made integral therewith. An adjusting nut 22 is fitted on the exteriorly threaded end of the sleeve 20, so as to permit adjustment and tightening of said sleeve. The arms 21 or 21^a of the several sleeves 20 in the plurality of brackets 7 are connected

together by a long link or rod 23, (Fig. 11), whereby all of said arms 21 and 21^a may be actuated in unison. Arm 21 differs from arms 21^a in having two pivots provided for connecting links thereto, while arms 21^a have a single pivot connection. When the bar 23 is moved in one direction, as for example, to the left in Fig. 11, the sleeves 20 will be turned in the brackets 7 and this turning movement will cause the screws 14 to be moved in a direction to the left, referring to Fig. 14, whereby the damper 6 which is carried by the bolts 13, will be moved toward and to the strings 5. When the rod 23 is moved in the opposite direction, as for example to the right in Fig. 11, the bolts 13 will be moved in the opposite direction and will thereby pull the damper 6 in a direction away from the strings 5. Thus the damper may be moved toward and away from and applied to and removed from the strings 5 by lengthwise movement of the bar 23.

As an arrangement for operating the bar 23, I show a rod 23^b connecting arm 21 to a bell crank lever 24 pivoted at 25 and pivotally connected with a rod 26 which is preferably extended downwardly in the longitudinal space or cavity 27 in the column 3. The lower end of the rod 26 is pivotally connected at 28 to a link 29 which is pivoted at 30 and whose other end is pivotally connected at 31 to a foot lever 32 having a projecting pedal 33. Thus by operating pedal 33 the damper 6 may be actuated to apply it or withdraw it from the strings. The pedal 33 is preferably arranged as one of a series of pedals, as shown in Fig. 2. It is provided with a spring 34 to hold it normally in an elevated position. The other pedals 35, 36, 37, 38, 39, 40 and 41, may be the pedals for sharpening the strings of a double action harp, the same being mounted in the base 1.

In order to permit the operation of the damper by hand as well as by foot, I show a hand lever 42 (Fig. 11), the same being pivotally mounted at 43. A bell crank end 44 of the hand lever 42 is pivotally connected to a link 45 which is in turn pivotally connected to the endmost arm 21^a, whereby by operating the lever 42, the link 23 will be shifted and the threaded bolts 13 operated to move the damper 6, as previously explained. In order that the hand operation of the rod 23 may not interfere or cause the operation of the foot lever 32 and associated parts, the link 23^b is preferably provided with a slot 23^a, permitting the longitudinal movement of the link 23^b in a

direction to the left, (Fig. 11), without moving the bell crank 24. The operation of the bell crank 24, however, by the rod 26 will shift the link 23 and 23^b so that the operation of the damper by foot power will be secured. In a similar manner the link 45 is provided with a similar slot 45^a, (Fig. 4), by which operation of the link 23 by foot power will not cause any movement of the hand lever 42.

It will be understood that changes and modifications may be made without departing from the spirit of the invention.

What I claim is:

In a harp the combination of a damper comprising a rod or bar arranged cross-wise and close to the upper ends of the strings, supporting brackets for said rod or bar, said brackets being secured to the neck of the harp, threaded bolts in said brackets and the bolts being connected with the damper, threaded sleeves surrounding the threaded portions of said bolts, crank arms on said sleeves, a single link connected with all of said arms and extending cross-wise of the harp strings substantially the entire length of said damper, whereby a longitudinal movement of said link will cause a corresponding axial rotary movement on the part of all of said eccentric arms so as to adjust said damper toward and away from the strings evenly throughout its entire length, a bell crank on the harp neck near the upper end of the column, said bell crank having a sliding pivotal connection with the adjacent end of said sliding rod or bar, a link arranged in said column and having its upper end connected with the other end of the said bell crank and its lower end extended down to the base of the column, a foot lever connected with the lower end of said last mentioned link for actuating the same by foot power, and a hand lever mounted on the harp neck on one side of the same, said lever being pivoted between its ends and one of its ends being formed in the shape of a handle for manual operation and the other end having a pin having a sliding connection with a supplemental link whose other end is pivotally connected with one of said eccentric arms, whereby said longitudinally adjustable link may be actuated by said hand lever and also whereby the actuation of said link by foot will not interfere with hand operation and vice versa.

In witness whereof, I hereunto subscribe my name this 17th day of July A. D. 1921.

WALTER I. KIRK.
